Inventor,
Horace W. Dover
C. H. Lockwood
Attorney.

UNITED STATES PATENT OFFICE.

HORACE WALTER DOVER, OF NORTHAMPTON, ENGLAND.

HANDWHEEL.

Application filed November 15, 1927, Serial No. 233,343, and in Great Britain November 19, 1926.

In the specification of my prior British Letters Patent No. 162,544 is described and claimed a hand wheel whereof the rim-portion is built up of annular inner and outer 5 peripheral portions, of which the inner peripheral portion is constituted by two parts each of concavo-convex cross-section arranged one within the other with their free edges spaced slightly from one another, and 10 of which the outer peripheral portion is of concavo-convex cross-section and shouldered or off-set inwardly at its marginal portions, so that said offset marginal portions may fit between the free edges of the two parts of 15 the inner peripheral portion of the rim and the outer surfaces of said inner and outer peripheral portions may be substantially continuous. In that specification it is also stated that the two constituent parts of the 20 inner peripheral portion, having been arranged the one within the other, are then pierced to receive the outer ends of the arms of the wheel, said outer ends are fitted in position and their junctions with the inner peripheral portion are then brazed, welded 25 or similarly treated so as to unite the parts.

In the specification of my prior British Letters Patent No. 162,499 is described and claimed an arm for a hand wheel formed 30 from sheet metal bent from a blank to the desired cross-section of arm required, the lateral marginal portions of the blank being inturned at what is to be, preferably, the underside of the arm, so as to form a dia- 35 phragm across, or strengthening rib within, the arm, and in this last-mentioned specification it is stated that the arm of that invention may be employed in connection with a rim-portion built up in accordance with the 40 first mentioned specification.

The object of the present invention is to strengthen the fixing of such and other arms to a rim-portion such, for instance, as one according to the first mentioned specification, for which purpose the inner part of the 45 inner peripheral portion of the rim-portion is formed with pockets or recesses corresponding in number and angular position with the arms of the wheel and with their 50 concavities presented towards the centre of the wheel, the outer part of the inner peripheral portion of the rim-portion is slit circumferentially of said portion and its margins are folded inwardly of said portion 55 to present apertures for the introduction

thereinto of the outer ends of the arms of the wheel, and, after said ends have been so introduced, molten metal is cast in the space surrounding said ends, thus embedding them and securing them firmly to the rim-portion. 60

If the arms of the wheel are to be of cast metal the securing of their ends to the rim-portion may be effected by casting the arms, including the metal in the pockets or recesses, in situ or the outer ends of previously cast 65 arms may be secured in the pockets or recesses as just described.

If the arms of the wheel are to be in accordance with the second mentioned specification there is no necessity to shoulder their 70 ends as before, but on the contrary, the tubular structure of the arms may be squeezed in at said ends in order to prevent molten metal from flowing thereinto and the more irregular the deformation of said structure, 75 the more firmly will said ends be embedded in, and secured by, the cast metal, whilst the absence of any thin cut edges presented in the circumferential direction precludes the possibility of any cutting action or undue 80 wear as result of e. g. the strain due to a sudden turning of the wheel.

Any suitable metal such as aluminium, brass, type-metal or like alloy may be employed for embedding the ends of previously 85 formed arms.

One form of the present invention is illustrated by the accompanying drawings, wherein Figure 1 is a partly sectional plan of a short length of the rim-portion of a 90 motor car steering wheel with an arm secured thereto; Figure 2 is a section on the line 2-2, Figure 1; Figure 3 is an end view of the arm alone, as seen from the outer end; and Figure 4 is a cross-section of the arm on 95 the line 4-4, Figure 2.

As shown the rim-portion of the hand wheel is built up of annular inner and outer peripheral portions, of which the inner peripheral portion is constituted by two parts 100 *a* and *b* arranged the one *a* within the other *b* with their free edges spaced slightly from one another, and of which the outer peripheral portion *c* is of concavo-convex cross-section and shouldered or off-set inwardly at its marginal portions, so that said off-set marginal portions may fit between the free edges of the two parts *a* and *b* and the outer surfaces of the portions *b* and *c* may 105 be substantially continuous. The part *a* is 110

formed with pockets or recesses such as *d* corresponding in number and angular position with the arms such as *e* of the wheel, whilst the part *b* is slit circumferentially of 5 said part and its margins are folded inwardly of said part as at *f* to present apertures for the introduction thereinto of the outer ends of the arms *e*.

Each arm *e* is formed in accordance with 10 my prior British Letters Patent No. 162,499, the tubular structure being squeezed in at its outer end in order to prevent molten metal from flowing there into and twisted out of its normal plane, as shown especially in 15 Figure 3, the more firmly to embed said end in, and secure it by, the cast metal, as herein-after set forth, whilst if the flattened end of the arm be drilled as at *g* this will assist the molten metal to flow from one side to the 20 other and also provide a more secure grip to prevent the arm from working loose.

After the outer end of an arm *e* has been introduced into the aperture between the inwardly folded margins *f*, molten metal, such 25 as aluminium, brass, typemetal or like alloy, is cast as at *h* into the space surrounding said end, thus embedding it and securing it firmly to the rim-portion. The cast metal may be employed also to round off the 30 corners externally of the rim-portion and arm *e*, as at *j*, so as to make a neat joint.

I claim:—

1. A hand wheel whereof the rim-portion is built up of annular inner and outer peripheral portions, of which the inner peripheral portion is constituted by two parts each of concavo-convex cross-section arranged one within the other with their free edges spaced slightly from one another, and 35 of which the outer peripheral portion is of concavo-convex cross-section and shouldered or off-set inwardly at its marginal portions, so that said off-set marginal portions may fit between the free edges of the two parts 40 of the inner peripheral portion of the rim and the outer surfaces of said inner and outer peripheral portions may be substantially continuous, the inner part of said inner peripheral portion being formed with 45 pockets or recesses with their concavities presented towards the centre of the wheel and the outer part of said inner peripheral portion being slit circumferentially of said portion and having its margins off-set to 50 present apertures for the introduction thereinto of the outer ends of the arms of the wheel, while, after said ends have been so introduced, molten metal is cast in the space 55 surrounding said ends, thus embedding them and securing them firmly to the rim-portion.

2. A hand wheel whereof the rim-portion is built up of annular inner and outer peripheral portions, of which the inner peripheral portion is constituted by two parts 55 each of concavo-convex cross-section ar-

ranged one within the other with their free edges spaced slightly from one another, and of which the outer peripheral portion is of concavo-convex cross-section and shouldered or off-set inwardly at its marginal portions, 70 so that said off-set marginal portions may fit between the free edges of the two parts of the inner peripheral portion of the rim and the outer surfaces of said inner and outer peripheral portions may be substantially continuous, the inner part of said inner peripheral portion being formed with pockets or recesses with their concavities presented towards the centre of the wheel and the outer part of said inner peripheral portion being slit circumferentially of said portion and having its margins off-set to 75 present apertures for the introduction thereinto of the outer ends of the arms of the wheel, said arms, including the metal 80 in the pockets or recesses, being cast in situ.

3. A hand wheel as claimed in claim 1, whereof the arms are each bent from a sheet metal blank, the marginal portions of said blank being inturned and forming a dia- 90 phragm within the arm, and the tubular structure of each of the arms at its outer end being squeezed in and twisted out of its normal plane.

4. A hand wheel whereof the rim-portion 95 is built up of annular inner and outer peripheral portions, of which the inner peripheral portion is constituted by two parts each of concavo-convex cross-section arranged one within the other with their free edges spaced slightly from one another, and of which the outer peripheral portion is of concavo-convex cross-section and shouldered or off-set inwardly at its marginal portions, so that said off-set marginal portions may fit between the free edges of the two parts of the inner peripheral portion of the rim and the outer surfaces of said inner and outer peripheral portions may be substantially continuous, the inner part of said inner peripheral portion being of sharper curvature than the outer part so that while said parts are tangential at the centre of their transverse curvature their free edges are spaced slightly from one another, and being formed with pockets or recesses with their concavities presented towards the centre of the wheel and the outer part of said inner peripheral portion being slit circumferentially of said portion and having its margins off-set to 100 present apertures for the introduction thereinto of the outer ends of the arms of the wheel, while, after said ends have been so introduced, molten metal is cast in the space surrounding said ends, thus embedding them and securing them firmly to the rim-portion.

5. A hand wheel as claimed in claim 1, whereof the arms are each bent from a sheet metal blank, the marginal portions of said 105

blank being inturned at the underside of said arm and forming a diaphragm within said arm.

6. A hand wheel as claimed in claim 1, whereof each arm is of substantially flattened oval cross-section with its underside V-shaped and is bent from a sheet metal

blank, the marginal portions of said blank being sharply inturned at said underside so as to lie contiguous with one another and forming a diaphragm lying substantially along the minor axis of the cross-section of said arm.

HORACE WALTER DOVER.
